UNITED STATES PATENT OFFICE.

RICHARD J. O'LEARY, OF CHICAGO, ILLINOIS.

COMB-CLEANER.

1,280,821.

Specification of Letters Patent. Patented Oct. 8, 1918.

Application filed February 9, 1917. Serial No. 147,587.

To all whom it may concern:

Be it known that I, RICHARD J. O'LEARY, a citizen of the United States, residing at Chicago, in the county of Cook and State 5 of Illinois, have invented certain new and useful Improvements in Comb-Cleaners, of which the following is a specification.

The invention relates to a device adapted to be used in cleaning the teeth of toilet 10 combs which are ordinarily made of some compound of which rubber forms the chief ingredient, or combs made of bone, metal or other materials. It is a well known fact that on account of the peculiar construction of 15 toilet combs, due to the close association of the teeth, there is a tendency for foreign materials to gather in the interstices or spaces between the teeth, and the removal of such foreign materials has been a rather tedious 20 and difficult process, as such foreign materials resist the action of water and other cleansing fluids, so that it is generally necessary to insert some instrument between the teeth to scrape and positively remove ac- 25 cumulations in cleaning the comb.

It is the primary object of my invention to provide a small inexpensive instrument that may be readily inserted between the teeth of the comb and quickly and effec- 30 tively remove accumulations from the adjacent inner surfaces of the teeth.

Other objects of the invention will appear in the following description of the preferred embodiment of the invention, as 35 shown in the accompanying drawing forming a part of the specification descriptive of my invention, and as more particularly pointed out in the appended claims.

Figure 1 is a view of a comb cleaner em- 40 bodying my invention.

Fig. 2 is a sectional view of the form of the device of Fig. 1 with parts including the handle removed or broken away.

Fig. 3 is an illustrative view showing the 45 manner in which the invention is applied to the teeth of a toilet comb during the operation of cleaning the same.

Referring to the drawings the reference character 10 designates a plurality of thin 50 metallic members spaced apart about the ordinary distance between the teeth of a comb. The metallic pieces 10 are preferably of spring steel sometimes termed "clock spring steel" which is preferably made quite 55 thin and ordinarily not much thicker than

the thickness of well calendered writing paper, in order that the edges of these spring steel members may be sharp enough to cut foreign materials on the inside edges of the teeth of the comb and scrape the teeth like 60 the edge of a knife blade to remove the accumulations therefrom in the manner described. The cleaner blades 10 are inserted between suitable spacing plates, designated by the reference character 13, and the plate 65 13^a at the middle of the cleaner blades is extended so that it provides a shank, as indicated in Fig. 1, to be inserted into a handle member 14 which may be formed of any suitable material as bone, celluloid, wood 70 or metal.

The manner in which the device shall be applied to the teeth of the toilet comb, for cleaning purposes, will be apparent from the fragmentary view of the comb in Fig. 3, 75 from which it will be seen that cleaner blades 10 of the device are inserted in the interstices between the comb teeth, and the edges of the cleaner blades are then caused to engage the sides of the comb teeth and have 80 the action of a knife blade when the operator twists the handle to cause the teeth to assume the position indicated by the dotted lines shown in Fig. 3, which latter are designated by the reference character 10^b. Obviously, the operation of inserting the cleaning blades between the teeth of the comb and giving the same a twist, causes the edges of the blades to scrape the contiguous surfaces of the teeth and then pulling the blades 85 outwardly, which operation will be continued until the operation of cleaning has been satisfactorily completed. Obviously, the device has the merit of being cheap to construct, is effective in its mode of opera- 90 tion, and when applied in the manner indicated, will clean or scrape all foreign materials from the interstices between the comb teeth, and will thoroughly scrape the contiguous surfaces between the teeth of the 95 comb.

After the device is used in the manner indicated, any foreign material, if not completely removed from the comb, will be found adhering to exposed surfaces of the comb teeth or comb back, and by the application of a cleansing fluid or a cloth, or both, the operation of thoroughly cleansing the comb will be completed.

I claim:

1. In a cleaner for combs, the combination 110

of a plurality of flexible metallic blades formed of clock spring steel, a plurality of plates arranged between said blades and being adapted to hold them in spaced relation, one of said plates being provided with an extension or shank, a locking pin passing through registering openings in said blades and said spacing plates, and a handle member for manipulating the device being attached to the said device by insertion over the shank of the said elongated spacing plate.

2. In a cleaner for combs, the combination of a plurality of flexible metallic blades formed of clock spring steel, a plurality of plates arranged between said blades and

being adapted to hold them in spaced relation, one of said plates being provided with an extension or shank, locking pins passing through registering openings in said blades and said spacing plates, and a handle member for manipulating the device being attached to the said device by insertion over the shank of the said elongated spacing plate. 20

In testimony whereof I have signed my name to this specification, in the presence of 25 a subscribing witness, on this 6th day of February, A. D. 1917.

RICHARD J. O'LEARY.

Witness:

ARTHUR L. SPRINKLE.
